UNITED STATES PATENT OFFICE.

WILLIAM P. KRAUSE, OF CHICAGO, ILLINOIS, ASSIGNOR TO MUMFORD MOLDING MACHINE COMPANY, OF CHICAGO, ILLINOIS, A CORPORATION OF NEW JERSEY.

PLUNGER-GUIDE CONSTRUCTION.

1,328,526.

Specification of Letters Patent.

Patented Jan. 20, 1920.

Application filed June 26, 1916. Serial No. 105,997.

To all whom it may concern:

Be it known that I, WILLIAM P. KRAUSE, a citizen of the United States, residing at Chicago, in the county of Cook and State 5 of Illinois, have invented certain new and useful Improvements in Plunger-Guide Construction, of which the following is a specification.

This invention relates to improvements 10 in plunger guide construction, and more especially to that type of molding machine in which a plunger or piston reciprocates in a cylinder. The main object is to provide, in combination with such machines, means 15 for guiding the reciprocal movement of the plunger, such means being adjustable to compensate for wear, and also functioning to lubricate the plunger member in its movement.

20 Another object resides in the provision of a plurality of plunger guiding means, each of which is separately adjustable, so that as one portion of the machine wears more than another, the greater wear may be 25 readily compensated for, thereby insuring proper centering of the plunger member and the allied mechanism. These and other objects of the invention will be more fully 30 set forth and described in the following specification and shown in the accompanying drawings, in which—

Figure 1 is a vertical section through a machine embodying my invention, the table thereof being shown in elevation.

35 Fig. 2 is a transverse section, taken along the line 2—2 of Fig. 1.

Fig. 3 is an elevation of one of the guiding members in position; and

40 Fig. 4 is a perspective view of the same disassembled.

Like numerals refer to like elements throughout the drawings in which 10 indicates the base of my machine, upon which is suitably mounted and attached a cylinder 45 11, in which the plunger 12 is arranged to reciprocate, said plunger carrying the mold table 13. This general type of machine is a plain jolt machine embodying therein what is known as the Mumford-Huggins 50 valve construction, illustrated and described in Patent No. 1,167,511, of January 11, 1916.

It is not believed to be necessary to describe the valve mechanism herein, as the same forms no component part of the present invention.

The plunger 12 is provided with three flattened surfaces 12^a, although I do not wish to be limited to the specific number, these surfaces being preferably equally spaced about the circumference of the plunger, as 60 clearly shown in Fig. 2. The cylinder 11 is provided with apertures 11^a therein, the same being located adjacent the flattened portions 12^a of the plunger, and surrounding these apertures are provided the out-standing collars 11^b.

Individual guiding members 14 are provided, the same being constructed with peripheral flanges or collars 14^a and arranged for attachment to the collars 11^b by means 70 of the studs or bolts 15, as shown in Fig. 2. These guiding members project into the cylinder 11, and abut against the flattened surfaces 12^a of the plungers, shims to any desired extent being interposed between the 75 flanges 14^a and the collars 11^b. The guiding members 14 are centrally apertured and hollowed out, as indicated by numeral 14^b, and the cavity so provided is filled with fibrous material, such as waste felt, or the 80 like, indicated by the numeral 17, the same being compressed to a suitable degree. A filler opening 14^c is provided, in which is threaded a plug 14^d, having an aperture 14^e therethrough, this aperture being normally 85 closed by a plug 14^f. Either the opening 14^c or the aperture 14^e may be utilized for pouring oil or other lubricant into the cavity 14^b, to saturate the fibrous material which bears 90 against the surface of the plungers and maintains the same in a constantly lubricated condition.

In the functioning of the apparatus shown, as wear takes place it may be compensated for by removal of one or more of 95 the shims, and consequent advancing of the guiding plugs or members, and, as often happens in this art, when the center of gravity of the load carried by the table 13 does not coincide with the axes of the plunger unequal 100 wear results on different surfaces of the plunger, rendering it advantageous to provide individual adjustable guiding members for the purpose of compensating for such unequal wear. This separate compensation 105 renders it possible properly to center and maintain in centered position the plunger. At the same time the construction above described maintains the plunger in lubricated condition.

It will be obvious that my invention is susceptible of numerous modifications or improvements, and I do not wish to be restricted to the form shown or described beyond the scope of the appended claims.

What I claim is:

1. In molding apparatus, in combination with a cylinder and plunger reciprocable therein, a plurality of separately adjustable guiding means adjustable relatively to said plunger and bearing thereagainst.
2. In combination with a cylinder having a reciprocable plunger therein, separately adjusting guiding members lying against said plunger, and lubricating means carried by each of said guiding members.
3. In combination with a cylinder having a reciprocable plunger therein, independently adjustable guiding members bearing against said plunger and lubricating means carried by said guiding means.
4. In combination with a cylinder having a plunger reciprocably mounted therein, separately adjustable guiding members carried by said cylinder and bearing against said plunger, and shims inserted between said guiding members and cylinder.

5. In combination, a cylinder, a plunger reciprocably mounted therein, said cylinder being provided with side apertures, and guide members inserted through said apertures and bearing against said plunger.

6. In combination, a cylinder, a plunger reciprocably mounted therein, said cylinder being provided with side apertures, flanges surrounding said apertures, and guide members inserted through said apertures and bearing against said plunger, said guide members being secured to said flanges.

7. In combination, a cylinder, a plunger reciprocably mounted therein, said cylinder being provided with side apertures, hollow guide members passing through said apertures into engagement with said plunger and being movable to provide for adjustment of said plunger, and lubricating means in said hollow guide members and in contact with said plunger.

In testimony whereof, I have subscribed my name.

WILLIAM P. KRAUSE.
